DESIGN FOR A SETTING FOR PRECIOUS STONES

Mitchall Waldman, New York, N. Y.

Application December 10, 1935, Serial No. 59,995

Term of patent 7 years

To all whom it may concern:

Be it known that I, Mitchall Waldman, a citizen of the United States and a resident of the Borough of Bronx, county of Bronx, city and State of New York, have invented a new, original, and ornamental Design for Settings for Precious Stones, of which the following is a specification, reference being had to the accompanying drawing, forming part thereof.

the setting of the present invention, showing a view of the interior of the same; and

Figure 2 is a view in side elevation of the same.

What I claim is:

The ornamental design for a setting for precious stones, substantially as shown.

In witness whereof, I have set my name to this specification this 3rd day of December, 1935.

MITCHALL WALDMAN.
